2,136,045

CONCRETE MIXER WITH TWO COMPARTMENT DRUM

John P. Faber, Dunellen, N. J., assignor to Ransome Concrete Machinery Company, Plainfield, N. J., a corporation of New Jersey

Application November 9, 1935, Serial No. 49,022

4 Claims. (Cl. 259—164)

The present improvements relate in general to concrete mixers and more particularly to that type of mixer wherein the ingredients of the batch are mixed in two compartments of a single drum, and are in the nature of an improvement in the co-pending application of James E. Bushnell and John P. Faber, Serial No. 632,878, filed September 13, 1932.

In former practice, the batch of ingredients for the mixing and placing of concrete comprising among others, sand, cement, crushed stone or coarse gravel, water, etc., was mixed in a single compartment drum for a prescribed interval and thereupon discharged. Such a structure imposes limitations on the capacity of the mixer. It is therefore an object of the present improvements to provide an improved single drum unit which increases the output of batches above sixty percent and improves the quality of the 'mix'.

It is a further object of the present improvements to provide improved means and methods of charging, mixing and discharging a concrete batch into and out of each of a plurality of mixing compartments in a single drum.

Novel means and methods are furthermore provided for charging, mixing, and discharging a concrete batch into and out of each of a plurality of mixing compartments in a single drum, while maintaining the rotary mixing movement of the ingredients. Accordingly, the improvements provide for the rotary mixing of the aggregate, water, etc., from the moment the first ingredients enter the first compartment, thence without interruption until the last compartment is discharged. The rotary mixing is therefore not interrupted but actually continues during transfer of the batch from one compartment to another.

A further object is to provide a novel type of mixing drum, having a plurality of compartments, whereby a batch may be mixed for part time in each compartment, so that while one batch is receiving its final partial mixing in the last compartment, another complete batch may be simultaneously receiving its initial partial mixing in the first compartment.

Another object is to provide an improved type of mechanism for transferring the partially mixed batch from one compartment to another, as well as an improved means for preventing transfer between such compartments. A further object is to provide novel mixing blades for transferring the batch from one compartment to another as well as a novel door or baffle for preventing trans-

fer, but likewise functioning in the operation cycle when open or closed.

An additional object is to provide an improved mechanism for accomplishing a continuous cycle of operation, including charging, mixing, transferring, mixing again and discharging a succession of batches in a series of compartments in a single drum unit.

Another object is to provide a novel reinforcement means for the blades, and also to provide a novel support for the closure or baffle.

A further object is to provide novel means and methods for operating a double-compartment drum.

Other objects include improvements in details of construction of double-compartment drums and in methods of their operation. Further advantages and objects of the improvements will be apparent to those skilled in the art upon reference to the accompanying specification and drawings, in which—

Fig. 1 is a longitudinal section through the mixer illustrating one embodiment of the improvements;

Fig. 2 is a section on line 2—2 of Fig. 1;

Fig. 3 is a section on line 3—3 of Fig. 1;

Fig. 4 is a section on line 4—4 of Fig. 1;

Fig. 5 is a diagrammatic showing of a modification, in plan view.

Referring to the drawings, the single rotary mixing drum 5 is provided with bearing bands or rings 6 upon which the drum revolves, being supported on a set of four bearings or supporting rollers (not shown). The drum is driven by a suitable power unit (not shown) through gearing in mesh with ring gear 7, fixed about the circumference of the drum, all as is common in the art.

The drum is equipped with the usual charging inlet 8, discharging outlet 9 and a transverse partition 10 which divides the drum into two mixing compartments 11 and 12. An opening 14 is provided in partition 10 for affording communication between the two compartments.

As illustrated the first compartment 11 may be provided with a series of mixing blades 15 and a series of mixing and transferring blades 16, while the second compartment is provided with a series of mixing blades 17. Any suitable charging means for the drum may be employed. In the illustrated embodiment the usual pivoted skip 18 is provided for introducing the dry aggregates, such as sand, cement, crushed stone and the like, into the first compartment 11. A

conduit 29 is usually provided for supplying water with the aforementioned batch.

The drum is discharged by means of the chute 19 which may be swung to full line position for that purpose, or to dotted line non-discharging (or mixing) position. This may be accomplished through a "power discharge" mechanism (not shown) similar to 24 provided for closure 20. Means for preventing transfer of the batch from one compartment to another is provided in the baffle or closure 20. As illustrated, this element is preferably in the form of a slideable door which may be reciprocated longitudinally of the drum. It is obvious that such a door may be made to slide across the opening 14, in a plane parallel to partition 10, if desired, without departing from the improvements.

The door 20 is preferably carried on an actuating rod 21 which extends to the exterior of the drum where it is operatively connected by levers 22 and rods 23 to a "power discharge" mechanism 24 of a type, such as that set forth in the patent to Shafer, 1,415,411 of May 9, 1922. In this manner the door 20 may be advanced and retracted from full to dotted line position and return, as desired, for opening or closing the opening 14. The transfer of the batch from compartment 11 to compartment 12 may thus be permitted or prevented.

A reinforcement in the form of a collar 25 is flanged and secured to the adjacent tips of transfer blades 16 (see Figs. 1 and 2). This element serves to reinforce and support the tips or free edges of the transfer blades which are adjacent the axis of the drum where they direct the batch through opening 14. Part of the most severe burden inflicted on blades 16, is imposed on them at this region, and the provision of the reinforcement 25 therefore affords a more rugged and durable construction. The vitality and efficiency 40 of the unit as a whole, is greatly increased.

In order to facilitate the operation, the door 20 is partially supported on collar 25 and bearing 26 by means of rod 21. The door is accordingly supported in alignment with openings 14 so as 45 to be readily movable relative thereto. It is noteworthy, that the closure 20 may be freely mounted on rod 21 so that the closure may rotate with the partition 10 and drum 5. Under some circumstances the rod 21 may also rotate and this is 50 permitted by providing a ball and socket connection 27, or other universal mounting where the rod joins the lever system. The door and rod may thus rotate with drum 5, either as a unit or independently of each other.

55 A timer or batch meter 50 actuated by handle 51 and rod 52 operated by the skip 18, is provided along with other mechanism (not shown) as set forth in the aforementioned co-pending application. This mechanism institutes and accomplishes a cycle of operation in a sequence as set forth in said application. This novel operation 60 may be described as follows:

With the drum 5 rotating with the parts in full line position in Fig. 1, compartment 11 is empty and chute 19 is in the position for discharging and emptying compartment 12. Upon pulling handle 51, mechanism is actuated whereby the skip 18 is elevated and the dry aggregates and water are charged into the mixing blades 15 of compartment 11. The batch is mixed in the rotating compartment 11 by the combined action of blades 15 and 16. The former mix the batch and advance it toward the central region of the compartment and blades 16 pick it up there and 70 further mix and advance the batch toward outlet 75

14. As shown by the arrow, the batch impinges the baffle or closure 20 and is returned to the compartment 11 for further mixing. The elements 15, 16 and 20 therefore give the batch a thorough mix by transferring it back and forth during the mixing operation. 5

When the batch has been given the predetermined partial mixing which it is to receive in compartment 11, the batch meter or timer 50 releases the mechanism which automatically operates and withdraws chute 19 from full to dotted line (closed) position. Thereupon mechanism is released which automatically operates member 24 for retracting closure 20 from full to dotted line (open) position. The drum 5 is rotating and the batch in 11 is being mixed therein, and the blades 16, while turning and mixing, direct and transfer the batch through opening 14 into the region of the rotating blades 17 in compartment 12. Without interruption in the mixing of the batch, the blades 17 pick up the batch and it thereupon is mixed by them in compartment 12.

The power discharge mechanism 24 thereupon retracts door 20 to closed position and then skip 18 feeds a new batch into compartment 11. This 25 new batch is given its initial partial mixing in compartment 11, and concurrently, the first batch is receiving its final partial mixing in compartment 12. The blades 17 mix the batch and advance it toward the middle and end of the compartment. When the prescribed partial mixing 30 is completed in compartment 12, the batch has been mixed for the full mixing interval required by building or highway specifications. The batch has received a "half mix" in each compartment, 35 the total of which is the equivalent of one full mix in a single compartment drum.

At this stage, the drum carries one completely mixed batch in compartment 12, and one partially mixed batch in compartment 11. The 40 power discharge mechanism (not shown) now swings chute 19 into discharging position (full line) whereupon batch #1 is discharged entirely from the drum. By the time this operation is completed, the partial mixing of batch #2 is 45 accomplished in compartment 11, so that the door 20 is opened and chute 19 withdrawn, whereupon batch #2 is transferred into compartment 12.

It is therefore seen that the operator's attendance is only required for actuating handle 51, 50 whereupon the complete cycle of operation just described, is accomplished without further attention.

If desired, the operation may be varied so that the control of the operator is injected at intervals 55 into the cycle. For example, certain of the mechanism may be disconnected from the batch meter and operated as follows:

When the skip 18 discharges its unmixed batch into the compartment 11, it sets a rod 52 60 of batch meter 50, so as to hold door 20 closed. While the batch is mixed in compartment 11, the operator may lower skip 18 to receive a second unmixed batch. When the partial mixing of batch #1 is completed (the proper interval having lapsed) the batch meter unlocks or releases the power discharge mechanisms and the operator may then cause the chute 19 to be swung out of compartment 12, and cause the door 20 to move into said compartment for uncovering opening 70 14. The parts are now in batch-transferring position and blades 16 transfer the batch into the region of mixing blades 17 in compartment 12. The door 20 may be thereupon closed and the operator may again actuate the mechanism for 75

elevating the skip with another batch, and for discharging compartment 12 by swinging chute 19 into same.

It may be found preferable to employ two batch meters, one with each power discharge mechanism. In such an arrangement, the operator may elevate the skip for charging compartment 11, whereupon the batch meter is set so as to lock closure 20 for the prescribed mixing interval for compartment 11, upon completion of which the power discharge mechanism controlling the closure is released and the operator may actuate a lever for retracting the closure. The discharge chute 19 is similarly locked by a second batch meter which upon completion of the mixing interval in compartment 12, releases the power discharge mechanism whereupon the operator may actuate another lever to throw the chute to discharging position. Both closure 20 and chute 19 automatically return to the original position after a predetermined interval, as is well known in the operation of power discharge mechanisms. Manifestly, such an organization involving two batch meters may be arranged for a complete cycle of automatic operation upon actuation of a single lever, as previously described.

The unit may also be operated in other ways, for example, like a single drum mixer. For example, the door 20 may be kept open and the batch mixed first in one compartment and then transferred and mixed in the second. The chute 19 may then be operated for discharging the completely mixed batch. On the other hand, a different operation may be followed wherein the chute 19 may be kept in discharging position, and a full mixing of the batch may be accomplished in compartment 11 with door 20 closed. The door may then be opened for transferring the batch to compartment 12 whence it is discharged as soon as blades 17 advance it to the chute 19.

It is significant that the blades in the first compartment act as mixing and transfer blades and direct the aggregates toward and downwardly into the blades in the second compartment so that even though partial mixing is accomplished in isolated compartments, the mixing goes on uninterruptedly before, during and after transfer. The character of the mixing operation in compartment 11 may be different from that in compartment 12, due to the difference of movement of the materials in each compartment. Furthermore, the participation of the door 20 in the mixing operation along with the blades in the center of the drum insures better and quicker mixing, and the presence of the door contributes to the improved quality of the batch.

The reinforcing collar is particularly advantageous since it secures the tips of the mixing transfer blades 16 together, and through the rod 21 and door 20, the partition 10 and blades 16 are braced and reinforced one by the other.

In providing the baffle or closure 20, the separation of the aggregates entering compartment 12 is prevented by breaking their fall. It also may retard the movement of aggregates from the door to the discharge chute. The closure 20 thus permits the simultaneous movement of the discharge chute to closed position and the closure to open or transferring position without danger of premature discharge of any portion of the partly mixed batch entering the second compartment from the first, and enables the operator to increase the speed of the operation. A skirt 55 may be provided on the sealing flange 75 of closure 20, for protecting the opening, but may

be omitted if desired. In preferred embodiments, a dished door with a single sealing flange, as seen in outline in Fig. 5, is employed.

A slightly modified form is diagrammatically illustrated in Fig. 5. The rod for actuating closure 20 is in the form of a tubular housing 21, which is moved by lever 22. The housing 21 carries the door 20 and the whole is partially supported by collar 25. A bifurcated support 10 extends through the housing 21 and through 10 the entire drum and extends from either end thereof where it is fixedly supported on the mixer frame. The support 10 insures alignment of the door and opening, and prevents any possibility of sagging of the door or its actuating means. 15

I claim:

1. A single drum concrete mixing machine, a transverse partition defining a first compartment and a second compartment for partially mixing batches of concrete in each, said partition having 20 a discharge opening, mixing blades in each of said compartments, means for charging said first compartment with water, sand, dry aggregate and cement, a movable door normally closing said opening, discharging blades for impelling the partially mixed batch through the opening obstructed by said door, a member operable from the exterior of said drum for opening said door and moving it into said second compartment whereby the partially mixed batch may be transferred and 30 a discharge means for said second compartment, and a connecting device whereby said member and door are supported by said discharging blades said device also forming a connection between 35 said blades.

2. A single drum concrete mixing machine, a transverse partition defining a first compartment and a second compartment for partially mixing batches of concrete in each, said partition having a discharge opening, mixing blades in each of 40 said compartments, means for charging said first compartment with water, sand, dry aggregate and cement, a reciprocating door normally closing said opening, discharging blades for impelling the partially mixed batch through the opening 45 obstructed by said door, a bearing supported by said blades, a connecting device joined to said bearing and connecting said blades, a member supported by said bearing and operable from the exterior of the drum for supporting and opening 50 said door whereby the partially mixed batch may be transferred to said second compartment, and a discharge means for said second compartment.

3. In a single drum concrete mixing machine having a transverse partition defining two compartments for partially mixing batches of concrete and a discharge opening in said partition through which said partially mixed batches are transferred from one compartment to the other, the combination of means for mixing batches in 60 both compartments, means for transferring a partially mixed batch from the first to the second compartment and for separating the batches in the two compartments during non-transferring periods, means extending to the exterior of the 65 drum and connected with said transferring and separating means in the interior of the drum for moving the said means and a bearing support for said moving means mounted in one of said compartments and connected with and rigidly connecting certain elements of said mixing means, to form therewith a unitary structure.

4. In a single drum concrete mixing machine having a transverse partition defining two compartments for partially mixing batches of con- 75

crete and a discharge opening in said partition through which said partially mixed batches are transferred from one compartment to the other, the combination of means for mixing batches in both compartments, means for transferring a partially mixed batch from the first to the second compartment and for separating the batches in the two compartments during non-transferring periods, means extending to the exterior of the drum and connected with said transferring and

separating means in the interior of the drum for moving the said means and a bearing support for said moving means mounted in one of said compartments and connected with and rigidly connecting certain elements of said mixing means, 5 to form therewith a unitary structure, said structure also supporting said transferring and separating means.

JOHN P. FABER. 10
